UNITED STATES PATENT OFFICE.

HERMAN E. S. LORENZ, OF CHAPPAQUA, NEW YORK.

COIL-BOX PROTECTOR.

1,339,568.

Specification of Letters Patent. Patented May 11, 1920.

Application filed December 15, 1919. Serial No. 344,805.

To all whom it may concern:

Be it known that I, HERMAN E. S. LORENZ, a citizen of the United States, residing at Chappaqua, county of Westchester, and State of New York, have invented a new and useful Coil-Box Protector, of which the following is a specification.

This invention is a coil box protector, particularly adapted for use on Ford cars. 10 In cars of this make, the coil box is mounted on the dash directly beneath the cowl, and the parts of the car are so constructed that in rainy weather water frequently finds its way through the joints which the cowl makes with the adjacent portions of the body construction, wets the dash and cowl box and short circuits the same.

Numerous expedients have been resorted to to overcome this defect but, in the major 20 part, they prove entirely ineffective, so that most Ford owners rely, at the present time, on the rubber tarpaulin which they drape over the hood and cowl and support the same on the wind shield brackets. This tarpaulin serves to shed the rain so that it does not come into contact with the joints adjacent the cowl.

As the Ford coil box is constructed, it embodies a wooden back to which the ignition 30 leads are attached, while the remainder of the coil box is formed from sheet metal. It has been heretofore suggested to place water proof material over the wooden back of the box for the purpose of rendering it impervious to moisture or water, but with these 35 constructions the water is found to work into the joints at the edges of the box, as well as to short circuit the porcelain plugs so that while such constructions assist, to some extent in overcoming the difficulties, they do not solve the problem.

With the foregoing considerations in mind, the object of the present invention is to provide a coil box protector which will 45 positively protect the coil box against rain which may leak through the car body and will not only render the box impervious to water but will also preclude short circuits at the porcelain plugs.

50 Features of the invention, other than those specified, will be apparent from the hereinbelow detailed description taken in conjunction with the accompanying drawings.

In the accompanying drawings, I have 55 illustrated one practical embodiment of the invention, but the construction therein

shown is to be understood as illustrative only, and not as defining the limits of the invention.

Figure 1 is a perspective view of a Ford 60 coil box embodying the present invention; and,

Fig. 2 is a section in the plane of the line 2-2 of Fig. 1.

Referring to the drawings, A designates, 65 a coil box which, in practice, is provided with a body a and a cover a' adapted to be normally locked in closed position by means of catches B, one of which is positioned at each side of the box. The box is provided 70 with a wooden back C whereas the rest of the box is formed from sheet metal. The sheet metal sides are provided with flanges D by means of which the back C is secured in place by screws passing through the 75 flange D and into the back C, and said sides are further provided with flanges E, which serve as attaching flanges for mounting the box in position on the dash.

Extending through the wooden back C 80 are a plurality of porcelain plugs F, which form the terminals of the box and which plugs are provided at their outer ends with binding nuts f to secure the wiring leads G to the plugs as clearly shown in Fig. 2. 85

In carrying out the present invention, I 90 completely cover the exterior of the back C with a water resisting medium H and this material I carry around the sides of the box as at h, for an appreciable distance, preferably from one-third to one-half the depth of the box. In practice, the material employed is rubber which is vulcanized in place as shown in the drawings, so as to tightly cling to all portions of the body and 95 back of the box with which it contacts so that water cannot work in between the rubber and the box and wet the back C. The attaching flanges E are preferably left uncovered so that they may be more readily 100 attached to the dash by means of bolts or screws in the usual manner. It will be noted, more particularly from Fig. 2, that the rear face of the back covering of rubber H, is flush with the attaching faces of 105 the flanges E and does not project beyond said faces of the flanges. Accordingly, there is no tendency during the attaching of the box to force the wooden back C loose from its supporting flanges D as is so frequently the case in such prior devices as provide a covering for the wooden back.

In order to preclude short circuiting of the porcelain plugs F, as would be the case if they were left to protrude uncovered from the back covering H, I preferably secure to the back covering H, by vulcanizing or otherwise, a plurality of rubber sleeves or tubes I which are formed from soft flexible rubber. These sleeves may be rolled back to the base of the plugs with 5 which they are associated as shown at the left hand plug in Fig. 2, to allow of the attaching of the leads G, but after the leads are attached they are adapted to be unrolled to partake of positions shown in connection with the other plugs of Fig. 2 to 10 completely envelop the plugs and an appreciable portion of the wire leads. The resulting construction is shown in Fig. 1, wherein it will be manifest that any water 15 coming in contact with the sleeves I near the base thereof will merely flow down over the sleeves and will not work up into the sleeves and come in contact with the connection. In vulcanizing the rubber covering in position on the box, it is formed to 20 fit over the cover a', but is not secured thereto, so that the cover may be removed in the usual manner to gain access to the interior of the box. Experience has shown 25 that Ford cars equipped with a coil box protector in the manner described would run indefinitely in all sorts of weather without short circuiting at the coil box due to water leakage and the use of tarpaulins or 30 other means is entirely unnecessary. The present invention may be applied to the coil box in a simple and economical manner and does not appreciably increase the cost of 35 the box. It thus overcomes one of the problems which has, for years, been troubling 40 Ford owners. In almost a great majority of cases ignition trouble in Ford cars are due to moisture or water in the coil box and this is obviated by the present invention. 45

It will be apparent that the specific structure described may be modified in formal respects, such as by the substitution of equivalents, without departing from the 50 spirit or substance of the invention, the scope of which is commensurate with the appended claims.

In the form of the invention shown and described, the water proof covering is re-

ferred to as being vulcanized in position on the box. However, the invention is not to be understood as restricted in this regard since, in practice, it may be made about a form or molded in a die and thereafter slipped over any stock box. 55

Having thus fully described the invention, what I claim as new and desire to secure by Letters Patent is:

1. A coil box protector embodying a layer of water proof material vulcanized to the back of the coil box and extending around the sides thereof, and flexible water proof sleeves having impervious joints with said layer of water proof material, one of said sleeves being associated with each terminal 70 of the box in such manner as to embrace the same and extend an appreciable distance beyond the end thereof.

2. A protector for coil boxes embodying a vulcanized covering of rubber adapted to 75 overlie the back of the box and from which covering projects a plurality of flexible, rubber sleeves, one of which embraces each terminal of the coil box and projects an appreciable distance beyond the outer end 80 thereof.

3. A protector for coil boxes embodying a water proof covering attached to the box and overlying the back of the box and a portion of the sides thereof and through 85 which water proof covering the terminals of the coil box project, a plurality of flexible water proof sleeves, one of which embraces each terminal and projects an appreciable distance beyond the end thereof, 90 the base of each sleeve being imperviously united to the water proof covering of the back of the box.

4. A protector for coil boxes embodying means secured directly to the box for rendering the back of the box impervious to water, and means extending from the back of the box at each terminal of the coil box to an appreciable distance beyond the end of a corresponding terminal and embracing 100 said terminal, whereby the terminals are individually protected to preclude water from coming into contact with the terminals of the box as well as with the connections between said terminals and the engine leads. 105

In testimony whereof, I have signed my name to this specification.

HERMAN E. S. LORENZ.
